(57) **CLAIM**

The ornamental design for a low profile oval light fixture, as shown and described.

DESCRIPTION

FIG. 1 is a perspective view showing my new design;

FIG. 2 is a bottom plan view thereof;

FIG. 3 is a top plan view thereof, the electric wires being shown broken away to depict indeterminate length;

FIG. 4 is a front view thereof; and,

FIG. 5 is a right-hand end view thereof, the left-hand end view being a mirror image thereof.
